DES. 116

4-17-1847

Ch 116

(120) STOVES & FURNACES
Heating Stoves.

Des. 116

W. P. Bixby, David Stuart, & L. A. Watson, (assignors of W. Bixby)
County of Philadelphia, Pennsylvania.
Letters Patent (Design No. 116) dated 17th April 1877.

The Schedule referred to in these Letters Patent and making part of the same.

To all whom it may concern Be it known that we W. P. Bixby, David Stuart, Jacob Bresly & Lehman A. Watson all of the County of Philad^a in the State of Pennsylvania have invented or produced a new and useful Design to ornament a cooking Stove and do hereby declare that the following is a full and exact description of the Design in connexion with the accompanying drawing.

Fig 1 Represents the front plate the upper edge of which is ornamented with a gothic molding as represented at a the sides of the plate are ornamented with a succession of scrolls as represented at b, b, and the edges of the plate are ornamented with a moulding represented at c, c.

Fig. 2. Represents the back plate, the centre of which is ornamented with an eagle seated between two cornucopias with extended wings and holding in his talons some arrows and standing on the edge of a shield and above its head are inscribed with the words "Nec plus ultra" ornamented with stars & beneath is hung a festoon of scrolls reaching to the bottom edge of the plate, the top edge of this plate is intended to be ornamented with the same gothic moulding that is placed on the front but it is also designed as in this instance to sometimes place the collar intended to receive the stone plate on the offset at the top of the plate see represented at a, the edge is ornamented with the same moulding as the sides of the front plate see b, b, Fig. 2.

Fig. 3. Represents one of the side plates, the other side plate is intended to match it exactly. The top edge is ornamented with the same gothic moulding as ornament the top edges of Fig. 1 & Fig. 2 see a. The sides and bottom the same as ornaments the sides of Fig. 1 & Fig. 2, see b, b, b, the centre of this plate is ornamented with a succession of scrolls and diamond shape figures all together forming a diamond and surrounded with a wreath of scrolls tastefully tied and knit together, it is intended whenever necessary requires it to place the collar intended to receive the stone plate sometimes on the offset at the top of this plate

Fig. 4. Represents the door intended to be placed in the front of the stone the edges are ornamented with a moulding represented at a a a a the centre is ornamented with a flower from behind which are seen to be starting two eagles holding

Des. 116

33

work as represented in the centre of Fig. 4.

Fig. 5. Represents the draft door intended to be placed in front below Fig. 4, the edges are ornamented with the same moulding as Fig. 4, see a a a the centre is ornamented with a beautiful arrangement of flower and leaf work see centre of Fig. 5.

It since thus described the ornamental Design for a coat stone and do hereby claim the exclusive right to the same as hereby laid out described and arranged but we do not claim the right to any one of the ornaments separately.

W. H. Cope

David Stuart

Rich. Peterson

W. P. Breson

D. M. Little.

Jacob Beasley

Schmidt Watson